SHEET METAL FOR METAL CONTAINERS OR THE LIKE

Klaus Burg, Forest Hills, and Archie G. Drummond, Wantagh, N. Y., and Walter Dorwin Teague, Annan-dale, N. J., assignors to The F. & M. Schaefer Brewing
Co., Brooklyn, N. Y., a corporation of New York

Application July 16, 1958, Serial No. 51,803

Term of patent 14 years

(Cl. D54—2)

Fig. 2

Fig. 1 is a plan view of the sheet metal for metal containers or the like showing our new design; and

Fig. 2 is an edge view of the sheet metal of Fig. 1.

The lining on the drawing represents contrasting colored areas.

We claim:

The ornamental design for a sheet metal for metal containers or the like, substantially as shown and described.
